UNITED STATES PATENT OFFICE.

CHARLES E. DATH, OF CHICAGO, ILLINOIS, ASSIGNOR TO WILLIAM H. MINER, OF CHAZY, NEW YORK.

CAR-UNDERFRAME.

1,214,148.

Specification of Letters Patent. Patented Jan. 30, 1917.

Application filed April 14, 1916. Serial No. 91,241.

To all whom it may concern:

Be it known that I, CHARLES E. DATH, a citizen of the United States, residing at Chicago, in the county of Cook and State of Illinois, have invented a certain new and useful Improvement in Car-Underframes, of which the following is a full, clear, concise, and exact description, reference being had to the accompanying drawings, forming a part of this specification.

This invention relates to improvements in car underframe structures.

The object of the invention is to provide an improved underframe structure for passenger cars, and more particularly for the platform and draft-rigging.

Another and more specific object of the invention is to provide an improved form of casting for passenger car platforms, which casting is not only adapted to support the buffer stems, but which is arranged to act as a front stop for the gear of the draft-rigging.

The invention furthermore consists in the improvements in the parts and devices and in the novel combinations of the parts and devices herein shown, described and claimed.

In the drawing forming a part of this specification, Figure 1 is a vertical, longitudinal sectional view of the end portion of a passenger car, showing my improvement in connection therewith. Fig. 2 is a horizontal sectional view taken substantially on the line 2-2 of Fig. 1. Fig. 3 is an enlarged, transverse, vertical sectional view taken substantially on the broken line 3-3 of Fig. 1. Fig. 4 is a vertical sectional view taken substantially on the line 4-4 of Fig. 1. Fig. 5 is a detailed perspective of the casting at the end of the car. And Fig. 6 is a detailed sectional view of the car structure adjacent the body bolster illustrating a modification of the structure shown in the other figures, the section of Fig. 6 corresponding to the section shown in Fig. 2.

Referring to said drawing, 10, 10 denote the center sills, 11, 11 the portions of the body bolster, 12 a filler plate of the bolster between the sills, and 13 the center pin cast-

ing of the bolster. Secured to the sills 10 and extending forwardly to the end of the car are channel shaped center sill extensions 14, 14, the latter having their flanges turned outwardly. Mounted between the sills and riveted to the center sills and center sill extensions is a rear stop casting 15, having a front vertical wall 16 which, at its lower portion, forms a stop for the rear end of the yoke 17 to abut against, and at its upper portion forms a rear stop for the buffer mechanism designated generally by the reference A. The buffer mechanism A is supported by inverted U-shaped plates 18, having a horizontal plate 118 secured thereto, which plates 18 are mounted between and bolted to the center sill extensions 14. Another plate 19 extends over the buffer mechanism to form a chamber therefor, said plate 19 having lateral flanges 20, 20, which are secured to the upper flanges of said sill extensions 14. The yoke 17 is arranged horizontally, and has the arms thereof slotted to receive a coupler key 21, said coupler key connecting the yoke to the draw bar 22. Mounted within the yoke 17 is a friction gear 23, said gear being between the rear follower 24 and the front follower 25. The platform extension is formed by a casting designated generally by the reference B, said casting B having a hollow forward extension 26, having three passageways 30, 31 and 32 extending therethrough, the passageways 30 and 32 being for the buffer side stems 33, and the center passageway 31 being for the main buffer stem 34. Said extension 26 of the casting B is preferably curved on its front face as indicated at 35 between the passageways 30 and 32. On its rear face, the casting B has a transversely extending shoulder 36 across the top thereof, which is adapted to abut one of the transversely arranged members 37 of the car floor. Suitable wear plates 38, 38 are detachably supported in the casting B for the buffer side and main stems. At its rear, the casting B is provided with a vertical wall 39, which is extended downwardly so as to form a transversely extending, hori-

zontal shoulder for the front follower 25 to abut against. At its sides, the casting B is provided with depending flanges 40, 40 riveted to the end sill of the car, and below the center passageway 31 the casting B is extended downwardly with a hollow, box-like formation 41, which fits between and is riveted to the center sill extensions 14. To form the lower front stop for the follower 25, a casting C is provided, the same being riveted to the lower flanges of the sills 14. Said casting C is provided on its upper face with a flat, horizontal table portion 42 on which the butt of the draw-bar 22 is adapted to slide, so that the draw-bar is properly supported in alinement with the gear, and the coupler key 21 relieved of the weight of the coupler. A carry iron 43 is provided to support the front portion of the coupler, said carry iron 43 being of angular cross-section and supported by bolts 44, which pass up through sleeves 45 and through a horizontal flange 46 formed in the casting B.

From the preceding description it will be seen that the casting B not only serves to support the stems of the buffer mechanism, but is so arranged as to provide a front stop for the front follower of the draft gear. Also, the casting 15 acts as a rear stop for both the gear of the draft rigging and the buffer mechanism proper. The draft gear 23 is supported in position by means of a detachable, channeled saddle plate 47. By removing said plate 47, the gear 23 can be dropped downwardly without disturbing the draw-bar, and in order to facilitate access to the buffer mechanism, the plates 18 are detachably secured to the sills 14 by bolts 48, so that by removing the bolts and the plates 18, which carry the table 118, the buffer mechanism A may also be withdrawn. In the latter instance, however, it would also be necessary to remove the yoke.

Referring to the modification shown in Fig. 6, the rear stop casting 116 is made integral with the bolster filler 49, thus minimizing the number of parts and forming a larger riveting area for the rear stop casting with the center sills.

Although I have herein shown and described what I now consider the preferred embodiment of my invention, the same is merely illustrative, and I contemplate all changes and modifications that come within the scope of the claims appended hereto.

I claim:

1. In car construction, the combination with buffer mechanism and a draft rigging, of a platform end casting having means for supporting the stems of the buffer mechanism and an integral front stop shoulder for the draft rigging.

2. In car construction, the combination with longitudinal sills, and a platform end

casting, of buffer mechanism, and a draft gear, the latter being located beneath the buffer mechanism and the gear and buffer mechanism being removable from below.

3. In passenger car construction, the combination with spaced, longitudinal sills, a rear stop casting extending between and secured to said sills and a front stop casting, of a buffer mechanism and a draft gear located between said sills and also between said castings. 75

4. In passenger car construction, the combination with longitudinal draft sills, a rear stop casting extending between and secured to said sills, and a front stop casting, the latter having a horizontal shoulder acting as a front stop for a draft gear and provided also with passage ways in which move the stems of a buffer mechanism, of a buffer mechanism and a draft gear located between said sills and also between said castings. 80

5. A casting for passenger car platforms having passage ways therethrough for the main and side stems of a buffer mechanism, said casting being provided with a horizontal, transversely extending front shoulder 95 for a draft gear.

6. A casting for passenger car platforms having passage ways therethrough for the main and side stems of a buffer mechanism, said casting being provided with a horizontal, transversely extending front shoulder 95 for a draft gear, said casting having also a front shoulder adapted to be engaged by the horn of a coupler to limit the rearward movement of the latter. 100

7. In car construction, the combination with draft sills, and a rear stop casting, of an end casting, a buffer mechanism, a draft gear, said mechanism and gear being located between said castings and arranged one above the other and removable from below, buffer stems extending through said end casting, a draw-bar coöperable with said gear, and a horizontal yoke operatively connecting said gear and draw-bar. 105

8. In car construction, the combination with a rear stop casting, and a front stop casting, the latter having a transversely extending shoulder at its rear end arranged to form the front stop for a draft gear, of buffer mechanism, and a draft gear, both said buffer mechanism and said gear being prevented from rearward movement by said rear stop casting. 115

9. In car construction, the combination with longitudinal sills, a rear stop casting, and a front stop casting, of a buffer mechanism located between said sills, a draft gear also located between said sills, and means 125 for detachably supporting said buffer mechanism above the draft gear, said means including a horizontal table extending between and secured to said sills above the draft gear. 120

10. In car construction, the combination with draft sills, and a platform end casting, of a buffer mechanism, a draft gear, and front, upper and lower, horizontal stop 5 shoulders for said draft gear, the upper front stop shoulder being formed integrally with said casting, and the lower front stop

shoulder comprising a casting secured to the bottoms of said sills.

In witness that I claim the foregoing I have hereunto subscribed my name this 17th day of March, 1916.

CHARLES E. DATH.
